UNITED STATES PATENT OFFICE

153,287

DESIGN FOR A SPECTACLE FRAME

Christopher Marmaduke Howell, South Croydon,
England

Application March 8, 1948, Serial No. 144,996
In Great Britain October 28, 1947

Term of patent 14 years

(Cl. D57—1)

To all whom it may concern:

Be it known that Christopher Marmaduke Howell, a subject of the King of Great Britain and resident of South Croydon, Surrey, England, has invented a new, original, and ornamental Design for a Spectacle Frame, of which the following is a specification, reference being had to the accompanying drawings, forming a part thereof.

Figure 1 is a front elevation of a spectacle frame, showing my new design.

Figure 2 is a side perspective view thereof, and Figure 3 is an underneath perspective view.

I claim:
The ornamental design for a spectacle frame, substantially as shown.
CHRISTOPHER MARMADUKE HOWELL.
